Primary Examiner—Charles A Rademaker(74) *Attorney, Agent, or Firm*—Holland & Hart, LLP(57) **CLAIM**

The ornamental design for a quadrant dental articulator base, as shown and described.

DESCRIPTION

FIG. 1 is a top and front top perspective view of a quadrant dental articulator base showing my new design;

FIG. 2 is a top and rear perspective view thereof;

FIG. 3 is a bottom and front perspective view thereof;

FIG. 4 is a bottom and rear perspective view thereof;

FIG. 5 is a left side elevation thereof;

FIG. 6 is a right side elevation thereof;

FIG. 7 is a top plan view thereof;

FIG. 8 is a bottom plan view thereof;

FIG. 9 is a front elevation thereof; and,

FIG. 10 is a rear elevation thereof.

The broken lines shown in the drawings are included for the purpose of illustrating environmental structures and form no part of the claimed design.

1 Claim, 4 Drawing Sheets# US D594,988 S
